UNITED STATES PATENT OFFICE.

JOHN J. DUFFIE, OF BERKELEY, CALIFORNIA, ASSIGNOR TO GOVERNMENT OF THE UNITED STATES.

CIRCUIT CLOSER.

Application filed July 9, 1918, Serial No. 244,092. Renewed January 11, 1922. Serial No. 528,588.

To all whom it may concern:

Be it known that I, JOHN J. DUFFIE, a citizen of the United States, residing at Berkeley, in the county of Alameda and State of California, have invented new and useful Improvements in Circuit Closers, of which the following is a specification.

This invention relates to circuit closers and more particularly to a thermostatically controlled circuit closing means especially adapted for use in connection with submarine mines, although the device is obviously susceptible to other applications.

One of the objects of this invention is to provide a thermostatic device of the above character which will automatically maintain a uniform distance between two contact points in an electric circuit, notwithstanding variations in temperature of the surrounding medium. Another object of this invention resides in the provision of a reliable and efficient thermostatic device which is capable of ready and delicate adjustments and is dependable in operation under trying working conditions. A further object of this invention is to provide a thermostatic circuit closing device of simple and practical construction especially adapted for use in connection with an electric firing circuit for exploding submarine mines.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof; all as more completely outlined herein.

My invention concerns especially an improved thermostatically controlled means to be used in connection with circuit closers for an actuated or firing circuit of a submarine mine, and the arrangement is such that any variations in temperature of the surrounding medium, particularly the water, affects equally two movable members carrying contacts or circuit closing means. However, on the closing of an actuating circuit, due to disturbances outside the mine or to the operation of a switch at a shore station, the thermostatic attachment to one

of the contact carrying members is affected, causing such contact carrying member to move relatively to the first contact carrying member, whereby after a predetermined interval of time the two contact members will be brought together to close the actuated or firing circuit. Thus, for example, the distance between the two contact members may be adjusted during the assembling of the mine, and the mine may then be used in waters of any temperature. Any variations in temperature of the surrounding water affect the two contact circuit closing means similarly and equally, leaving the same amount of relative movement to be accomplished by one of the contact carrying members on the closing of the actuating circuit.

To enable others skilled in the art so fully to comprehend the underlying features thereof that they may embody the same in the numerous modifications in structure and relation contemplated by this invention, drawings depicting a preferred form have been annexed as a part of this disclosure, and in such drawings, like characters of reference denote corresponding parts throughout all the views of which:

Fig. 1 is a front plan view of my device; Fig. 2 is a cross-sectional view of the device taken along the line 2—2 of Fig. 1, the contact arms and the thermostatic coil being shown in entirety for the sake of clearness; and Fig. 3 is a view taken along the line 3—3 of Fig. 2, with certain parts shown broken away for the sake of clearness.

The device in question comprises a casing 5, consisting of a face plate 6 and a rear plate 7, spaced from each other at various points by suitable tubular insulating members 8, through which pass bolts 10. The heads of the bolts rest against one of the plates, but the threaded end of the bolts are insulated from the other plate by means of insulating washers 11, the bolts being secured by nuts 12, bearing against said washers. By means of this connection, the front and rear plates of the casing or housing 5 are insulated from each other.

A dial 13 is supported within the housing and is provided on one face thereof with suitable graduations 14, providing a convenient means of reference when adjusting the distance between contact carrying arms 15 and 16, later to be described. An

opening or window 17 is provided in the face plate 6 whereby the position of the contact carrying arms 15 and 16, with relation to the dial, may be observed.

5 A supporting plate 18 is secured to the rear plate 7 of the casing in any suitable manner, as by bolts or rivets 20, and to the front face of this plate the disc 13 is fastened, as by means of rivets 21. A shaft 22, 10 passes through supporting plate 18, and is provided with a bearing 23 therein, the opposite end of the shaft resting in the bearing 24, secured to the rear plate 7. A similar supporting plate 25 is secured to face 15 plate 6, and shaft 26, carrying the contact arm 16, has a bearing in this plate at 27. The opposite end of shaft 26 rests in the bearing 28, attached to the face plate, the shafts 22 and 26 being held in proper position by means of cotter pins 30 and 31, or other suitable retaining means. To the outer end of arm 15 a platinum, or other suitable contact point 32 is secured, while the outer end of arm 16 carries a suitable 20 contact pin 33, adapted to coat with the contact point 32 to close an actuated or firing circuit of the mine when the arm 15 is moved around adjacent the arm 16.

A bi-metallic thermostatic coil 34 surrounds shaft 22 and is secured thereto at its inner end, the outer end of said coil being adjustably held in a lug 35 by means of a set screw 36. A similar bi-metallic thermostatic coil 37 surrounds the lower 35 end of shaft 26, the inner end of the coil being secured to the shaft 26, the outer end of the coil being adjustably secured by a lug and set screw not shown. By means of the lugs and set screws, just described, the initial position of the contact arms 15 and 16 may be adjusted with reference to the arcuate dial 14 in an accurate and convenient manner. The bi-metallic coils 34 and 40 37 just described are of duplicate construction, being composed of two metals of different co-efficients of expansion. As the coils are wound in the same direction, it will be seen that any variation in temperature of a surrounding medium will affect the two 45 coils alike, causing them either to expand or contract equal amounts, whereby the contacts 32 and 33 are still maintained a predetermined distance apart.

The bi-metallic coil 34 is wound around 50 with a flexible resistance wire 40 connected to an actuating circuit 41, and the arrangement is such that when the actuating circuit is closed, as by means of a switch 42, current passes through the resistance wire 40, heating the bi-metallic coil 34, and causing the contact arm 15 to move towards arm 16. After a predetermined interval of time, dependent on the adjustment of the arms, the strength of the current in the 55 actuating circuit 41, the character of the

resistance wire 40, and the number of turns of the resistance wire around the bi-metallic coil 33, etc., the arm 15 will be moved around to a position where its contact 32 engages the contact 33, and the actuated or 60 firing circuit 43 of the mine is then closed, acting on a member 46 to effect the exploding of the mine. Current from the actuated circuit 43 is brought into the casing from one side thereof through the binding post 75 44 and goes out the other side through binding post 45, having passed through the shafts 22 and 26, the contact arms 15 and 16, the circuit being completed through the contact 33 and the contact pin 32, when 80 the arm 15 has been moved adjacent the arm 16.

It may thus be seen that I have provided a simple and practical device adapted to compensate for any general changes in temperature occurring adjacent to the contact members. At the same time I have provided a device which will be extremely delicate and accurate in its operation should the 85 thermostatic heating circuit be closed.

Without further analysis, the foregoing will so fully reveal the gist of this invention that others can by applying current knowledge readily adapt it for various applications without omitting certain features that, 90 from the standpoint of the prior art, fairly constitute essential characteristics of the generic or specific aspects of this invention, and therefore such adaptations should and are intended to be comprehended within the 95 meaning and range of equivalency of the 100 following claims.

All matters set forth and claimed in application Serial No. 185,245 filed August 9, 1917, and in application Serial No. 215,970 filed February 8, 1918, both in my name, are 105 reserved for said applications and hence are not claimed herein.

I claim as my invention the following:

1. In an electric circuit closer, in combination, contact carrying members, thermostatic coils for moving said contact carrying members, and electrical means associated with one of said coils for causing a relative movement of said contact carrying members.

2. In an electric circuit closer, in combination, contact carrying members, thermostatic coils for moving said contact carrying members, electrical means associated with one of said coils for causing a relative movement of said contact members, and means for initially adjusting the position of one of said contact members relative to the other.

3. In an electric circuit closer, in combination, contact carrying members, thermostatic coils for turning said contact carrying members, electrical means associated with one of said coils for causing a relative 120 movement of said contact members.

movement of said contact members, and means whereby one of said thermostatic coils may be adjusted relative to the other.

4. In an electric circuit closer, in combination, contact carrying arms, thermostatic means associated with each of said arms, and electrical means associated with one of said thermostatic means for causing a turning movement of one of said arms relative to 10 the other.

5. In an electric circuit closer, in combination, movable arms, a contact point on one arm and a contact pin on the other arm, thermostatic means cooperating with said 15 arms, and electrical means associated with one of said thermostatic means for causing a relative movement of said arms.

6. In an electric circuit closer, in combination, an actuated circuit, an actuating 20 circuit, movable contact arms connected to the opposite sides of said actuated circuit, a shaft attached to each of said arms, a thermostatic coil surrounding each of said shafts and attached thereto, and a flexible 25 resistance wire wound around one of said coils and connected to said actuating circuit for causing relative movement of said arms on the closing of said actuating circuit.

30 7. In an electric firing device for submarine mines, in combination, a casing including a front and rear plate, means for insulating said plates from each other, a dial secured between said plates, and a pair 35 of circuit closing arms disposed in front of said dial.

8. In an electric firing device for submarine mines, in combination, a casing including a front and rear plate, means for 40 insulating said plates from each other, a dial secured between said plates, adjustable circuit closing arms disposed in front of said dial and normally separated from each other, and means for bringing said 45 arms together.

9. In a firing device for submarine mines, in combination, a casing, including a front and rear plate, a disc secured between said plates and provided with a dial, electric contact carrying arms disposed in front of 50 said dial, thermostatic means associated with said contact carrying means, and means for adjusting said thermostatic means.

10. In an electric firing device for submarine mines, in combination, a casing including a front and rear plate, means for insulating said plates from each other, an electric circuit connected to each of said front and rear plates, thermostatically controlled contact arms electrically associated with said plates, and means associated with one of said arms for causing it to move relative to the other arm. 55

11. In an electric firing device for submarine mines, in combination, a casing including a front and rear plate, means for insulating said plates from each other, contact carrying arms, adjustable thermostatic coils attached to said arms, an electric circuit connected on either side to said front and rear plates, and electric means associated with one of said thermostatic coils for imparting relative movement to said arm. 65

12. In an electric firing device for submarine mines, in combination, a casing including a front and rear plate, means for insulating said plates from each other, an electric circuit connected at either side to said front and rear plates, circuit closing arms normally separated from each other and electrically associated with said plates, a thermostatic coil attached to one of said arms, a flexible resistance wire wound around said coil, and an actuating circuit connected to 80 said resistance wire. 75

Signed at Newport, Rhode Island, this 17th day of June 1918.

JOHN J. DUFFIE.
